ARTHUR BESSEY SMITH, OF EVANSTON, ILLINOIS, ASSIGNOR, BY MESNE ASSIGNMENTS, TO AUTOMATIC ELECTRIC INC., OF CHICAGO, ILLINOIS, A CORPORATION OF DELAWARE.

SUBSTATION TELEPHONE CIRCUIT.

Application filed May 22, 1922. Serial No. 562,633.

The present invention relates in general to sub-station telephone circuits, but more especially to sub-station telephone circuits for automatic telephone systems; and the object of the invention is to provide novel and improved circuit arrangements for an automatic desk telephone.

More specifically, the principal object is to produce a desk telephone circuit of the so called "booster" type, and further characterized by the inclusion of a direct current or non-polar receiver, by the high efficiency impulsive circuit employed, and by the use of a minimum number of conductors in the cord connecting the telephone proper with the bell box.

A further object is to provide standard terminal and wiring arrangements in a desk telephone of the character described above whereby the circuit may be readily changed to any desired one of a plurality of other circuits.

Having set forth the object and scope of the invention in general terms, the circuits and apparatus involved will now be explained more in detail, reference being had to the accompanying drawings, in which Fig. 1 is a wiring diagram of an automatic desk telephone and bell box, Fig. 2 is a simplified circuit diagram, while Fig. 6 is a schematic diagram of the impulsive circuit.

Figs. 3, 4, and 5 are other desk telephone circuits which may be readily produced from the circuit shown in Figs. 1 and 2, as will be described shortly in connection with Fig. 1. More particularly,—

Fig. 3 is a simplified circuit diagram of an anti-side tone desk telephone with a polar receiver.

Fig. 4 is a simplified circuit diagram of a series type desk telephone without an induction coil and with a non-polar receiver.

Fig. 5 is a simplified circuit diagram of a "booster" type desk telephone with a polar receiver.

Referring to Fig. 2, the talking circuit, as before stated, is of the booster type with a non-polar receiver. With the receiver removed from the switch-hook, the winding 4 of the induction coil, receiver R, and transmitter T, are bridged across the two line conductors 2 and 3. A shunt path may also be traced around the transmitter T, which path extends from the upper terminal of

transmitter T switch-hook springs 6 and 7 55 winding 5 of induction coil, condenser C, impulse springs 16 and 15, and hook springs 9 and 8 to the lower terminal of the transmitter. With talking battery connected to the two line conductors 2 and 3, the condenser C will be charged due to the difference in potential across the upper and lower terminals of the transmitter T, the amount of charge depending on the voltage across the transmitter terminals. As the resistance of the transmitter is increased, the main line current is reduced and the charge of the condenser is increased. Windings 4 and 5 of the induction coil are so connected 60 that the charging current induces in the primary winding 4 a current which is in opposition to the main line current, thereby further reducing it. When the resistance of the transmitter is reduced, the condenser discharges through the winding 5 and this 65 time induces a current in winding 4 which assists the main line current. By this arrangement the well-known "booster" effect 70 takes place.

For receiving incoming signals, the ringer 80 M is provided, which is normally bridged across the line independent of control by the switch-hook. It will be observed that the ringer bridge includes a condenser, and that this condenser is the same one included in 85 the shunt circuit of the transmitter.

Associated with the lower side of the line is the subscriber's impulse sender, or calling device, which is indicated by the reference character S. This sender may be of 90 the type which is shown and described on pages 34 and 35 of "Automatic Telephony" by Smith and Campbell, published by McGraw-Hill Book Company. It comprises essentially a pair of impulse springs 15 and 95 16 which are controlled by a cam (not shown) through the medium of a finger hole dial (not shown), and three shunt springs 12, 13, and 14, together with suitable means for retaining these springs in the position 100 shown in the drawing when the calling device is not in use, and for causing all three springs to come into engagement with each other when the calling device dial is turned from its normal position. The impulse springs 15 and 16 are connected in series 105 with the lower line conductor 2, and their function is to produce momentary interrup-

tions of the line circuit for the purpose of operating the central office switches. The function of the shunt springs 12, 13, and 14 is to short circuit or shunt the transmitter 5 T and the receiver R while the calling device is being operated to send impulses. To accomplish this, spring 12 is connected to one side of the receiver, spring 13 is connected to the junction of the other side of the receiver and one side of the transmitter, while spring 14 is connected to the other side of the transmitter, and it will be evident that with the springs connected in this manner, when they are brought into engagement, the 10 receiver and transmitter will be short circuited as stated.

In Fig. 1 the circuits have been drawn out in detail, corresponding parts being indicated by the same reference numerals as in 20 Fig. 2. The apparatus at the right of the drawing, comprising the transmitter T, the receiver R, the hook-switch H, and the calling device S, constitutes the desk telephone proper; while the apparatus to the left of 25 the drawing, comprising the ringer M, the condenser C, and the induction coil I is separate from the telephone and in accordance with the usual practice is located in the bell box. The telephone is provided with a terminal strip P in the base thereof, and the bell box is provided with a terminal strip P'. The various circuits are completed by means 30 of a cord which connects the two terminal strips which, it will be observed, comprises 35 only three conductors. The line extending to the exchange is connected at the terminal strip P' as illustrated in the drawing.

The operation of the substation circuit is as follows: When the receiver is removed 40 to initiate a call, the switch-hook contact springs 7 and 9 come into engagement with the contact springs 6 and 8, respectively, whereby the transmitter T is bridged across 45 the line in series with the receiver R and the primary winding of the induction coil, and the secondary winding is connected in 50 shunt of the transmitter in series with the condenser C. Responsive to the closure of the switch-hook springs, current is supplied 55 to the transmitter and receiver from a bridge battery at the central office (not shown) over the following path: line conductor 3, winding 4 of the induction coil, receiver R, transmitter T, switch-hook springs 8 and 9, and 60 the impulse springs 15 and 16 to the line conductor 2. The bridge at the central office, which includes the battery, may also 65 in accordance with the usual practice include the controlling relay of an automatic switch, the circuit of the controlling relay including 70 therefor the transmitter and receiver bridge at the telephone. It follows that by suitably manipulating the calling device dial, the calling subscriber may produce a series of 75 interruptions in the circuit of the controlling 80

relay to bring about the operation of the switch.

Considering a little more closely the operations which take place at the telephone during the transmission of a series of impulses, it will be noticed that as soon as the dial is turned from its normal position, the shunt springs are closed together, and the substation loop is completed over a path which may be traced from the line conductor 3 by way of winding 4 of the induction coil, shunt springs 12, 13, and 14, switch-hook springs 8 and 9, and the impulse springs 15 and 16 to the line conductor 2. It will be seen that the receiver and the variable resistance of the transmitter are excluded from the switch control during the entire time that the calling device is in operation, and are included again in the bridge across the line only when the calling device dial returns to its normal position. The shunting of the receiver takes care of the usual requirement of silent operation, so that the subscriber is not annoyed by hearing clicks in the receiver caused by the interruptions of the line circuit. Another result accomplished by the short circuiting of the transmitter and receiver is the reduction of the impedance of the shunt circuit connected around the ringer M, which includes only the windings 4 and 5 of the induction coil. 90

To continue, the first operation of the calling device brings about the operation of the first selector switch at the exchange, and succeeding operations of the calling device will now result in the operation of additional switches until the connection is finally completed to the line of the called subscriber, it being understood that all of the switches are provided with controlling relay bridges which, with the exception of the bridge in the last switch, are successively cut off from the line after their associated switches are operated. 100

The connection having been completed, 110 conversation may be held as desired, the talking circuits functioning the same as usual in such cases. The receiver is replaced at the end of the conversation, the circuits of the transmitter and receiver are broken at 115 the switch-hook contacts, and further flow of direct current through the substation from the exchange is prevented. As a result, all the switches used in the connection at the central office are released and restored to 120 normal in the usual manner. The substation is now in condition to receive incoming signalling currents which may come in over the line conductors 2 and 3, and pass through the ringer M and condenser C, whereby the 125 ringer is actuated to advise the subscriber that he is being called. It is noted that with the receiver on the hook, contact springs 6 and 7 are separated and the shunt around the ringer M is broken. 130

The impulse transmitting circuit which, as before stated, is exceedingly efficient and reliable is shown in schematic form in Fig. 6, which shows the condition of the circuit 5 through the substation when the dial is away from its normal position, in other words, when the impulses are being transmitted. The essential elements are the impulse springs, the permanent bridge including the condenser and the ringer, and the shunt around the ringer which includes the windings 4 and 5 of the induction coil. Since all the non-essential elements, such as contact springs, etc., and the elements which 10 are short circuited are omitted in the schematic drawing, the relation between the parts shown may be perceived at once. It will not be necessary to go into a minute consideration of the operation of its circuit 15 from a strictly technical standpoint, as there are a large number of different line conditions which might enter into a theoretical discussion of the electrical properties of the circuit, and a thorough treatment of the 20 subject would become exceedingly complicated. It may be stated, however, that a certain amount of capacity connected in shunt of the impulse springs is an advantage under a great many line conditions, especially if there is a considerable amount 25 of loop resistance. Notwithstanding this, when the condenser and ringer are permanently connected across the line in the usual manner without shunting the ringer, the condenser injuriously affects the impulses because of the exceedingly high impedance of the ringer which is in series with it, as this causes the condenser to charge and discharge 30 very slowly. For instance, if we consider 35 Fig. 6 and assume that the induction coil windings 4 and 5 are omitted, when the calling device springs are closed, the condenser bridge is short circuited and the condenser will be discharged. At each interruption of 40 the circuit, the line relay of the switch at the exchange, if it operates properly, should deenergize at once, but with the calling device springs open the condenser bridge is left across the line, and the condenser is immediately charged in series with the line relay. Owing to the fact that this charging 45 circuit also includes the high impedance ringer, the condenser will charge slowly and the resulting current flow will be prolonged 50 appreciably, thereby causing the deenergization of the line relay to be delayed. In other words, the effect of the condenser and ringer bridge is to make the line relay sluggish in responding to interruptions in 55 the line circuit.

Let us consider now the circuit with the induction coil windings present, connected as shown in Fig. 6. The benefit derived by having the induction coil windings connected in shunt of the ringer while impulses are

being transmitted, seems to be due to the fact that the condenser is caused to charge and discharge very much more rapidly. The impedance of the induction coil windings is almost negligible and it will be evident, therefore, that with the circuit of Fig. 6, the condenser will charge and discharge much more rapidly, and the charging current through the line relay will not be prolonged as in the former instance where the 70 induction coil windings were not connected in shunt of the ringer, with the result that the line relay is deenergized much more promptly when its circuit is interrupted.

Having described the new desk telephone 80 having the new circuit, a brief explanation will now be given of the manner and means by which this circuit may be conveniently changed into several other types of desk telephone circuits.

As before stated, the telephone is equipped 85 with a terminal strip P to which the different pieces of apparatus required to make up a complete automatic desk telephone are connected. The terminal strip P has a series 90 of binding posts as indicated to which wires with attached terminal clips can be easily and readily connected or disconnected. The conductors of the cord leading to the bell box, the conductors of the calling device S, the conductors of the receiver cord, and the 95 wire "X" are all equipped with such attached terminals so that they are easily interchangeable. The other conductors are permanent, and may be soldered directly to lugs on their respective binding posts as 100 shown in Fig. 1.

With the above arrangement of terminals the different types of desk telephone circuits shown in Figs. 3, 4, and 5 can be readily obtained. The following code gives the 105 changes that are necessary.

Fig. 3. Anti-side tone telephone circuit with polar receiver.—Move receiver conductor from terminal 25 to terminal 27; move receiver conductor from terminal 22 to terminal 24; move wire "X" from terminal 27 to terminal 22; and change to polar receiver.

Fig. 4. Series circuit with a non-polar receiver.—Omit induction coil, and connect together terminals 34 and 36 at the terminal strip P' in the bell box.

Fig. 5. Booster telephone circuit with polar receiver.—Move receiver conductor from terminal 25 to terminal 27, move wire "X" from terminal 27 to terminal 22; and change to polar receiver.

The circuits shown in Figs. 3, 4, and 5 form no part of the present invention and consequently will not be described in detail. It may be stated, however, that the circuit shown in Fig. 5 is illustrated and described in the co-pending application of Martin, Serial No. 452,467, filed March 15, 1921; that the circuit shown in Fig. 3 is the same as the 125 130

circuit of Fig. 5 except that the local receiver circuit excludes the transmitter; and that the circuit shown in Fig. 4 is substantially the same as the well known "series" circuit which is in common use throughout the country.

While the explanation might perhaps be further amplified, it is believed that the foregoing will be sufficient to enable the invention to be understood and used by those skilled in the art. It will be seen that I have devised an especially advantageous circuit for an automatic desk telephone, which includes an impulse transmitting circuit of high efficiency and which, in addition, uses a non-polar receiver and has the various parts so arranged that the minimum number of conductors connecting the bell box with the desk stand is maintained; while at the same time the various parts are so arranged and terminals are provided such that different types of telephone circuits can be readily obtained by simply changing a few conductors, and without having to open or change soldered connections.

Having described the invention, what I consider to be new and desire to have protected by Letters Patent will be pointed out in the appended claims.

30 What I claim is:

1. In a substation telephone set, an induction coil, a transmitter, a receiver, and one winding of said induction coil in bridge of the line, a ringer and a condenser in a second bridge of the line, a local circuit connecting the two terminals of said transmitter and including said condenser and the second winding of said induction coil, an impulse sender for producing interruptions in the said first bridge to transmit impulses over the line to the exchange, the said second bridge remaining closed meanwhile, and means for closing a low impedance shunt circuit around the said ringer while the said sender is being operated.
2. In a substation telephone set, an induction coil, a transmitter, a receiver, and one winding of said induction coil in bridge of the line, a ringer and a condenser in a second bridge of the line, a local circuit connecting the two terminals of said transmitter and including said condenser and the second winding of said induction coil, an impulse sender for producing interruptions in the said first bridge to transmit impulses over the line to the exchange, the said second bridge remaining closed meanwhile, means for closing a low impedance shunt circuit around the said ringer while the said sender is being operated, and means for short-circuiting the said transmitter at the same time.
3. In a substation telephone set, an induction coil, a transmitter, a receiver, and one winding of said induction coil in bridge of the line, a ringer and a condenser in a

second bridge of the line, a local circuit connecting the two terminals of said transmitter and including said condenser and the second winding of said induction coil, an impulse sender for producing interruptions in the 70 said first bridge to transmit impulses over the line to the exchange, the said second bridge remaining closed meanwhile, and means for connecting the two windings of said induction coil in parallel with the said ringer while the said sender is being operated.

4. In a substation telephone set, an induction coil, a transmitter, a receiver, and one winding of said induction coil in bridge of the line, a ringer and a condenser in a second bridge of the line, a local circuit connecting the two terminals of said transmitter and including said condenser and the second winding of said induction coil, an impulse sender for producing interruptions in the said first bridge to transmit impulses over the line to the exchange, the said second bridge remaining closed meanwhile, a shunt circuit around the said ringer including the two windings of said induction coil and the receiver, and contacts for short-circuiting said receiver while the said sender is being operated.

5. In a substation telephone set, an induction coil, a transmitter, a receiver, and one winding of said induction coil in bridge of the line, a ringer and a condenser in a second bridge of the line, a local circuit connecting the two terminals of said transmitter and including said condenser and the second winding of said induction coil, an impulse sender for producing interruptions in the said first bridge to transmit impulses over the line to the exchange, the said second bridge remaining closed meanwhile, and contacts actuated only during the operation of said sender for connecting one winding of said induction coil in a shunt path around said ringer.

6. In a substation telephone set, an induction coil, a transmitter, a receiver, and one winding of said induction coil in bridge of the line, a ringer and a condenser in a second bridge of the line, a local circuit connecting the two terminals of said transmitter and including said condenser and the second winding of said induction coil, an impulse sender for producing interruptions in the said first bridge to transmit impulses over the line to the exchange, the said second bridge remaining closed meanwhile, and contacts actuated only during the operation of said sender for short-circuiting said transmitter.

7. In a substation telephone set, an induction coil, a transmitter, a receiver, and one winding of said induction coil in bridge of the line, a ringer and a condenser in a second bridge of the line, a local circuit connecting the two terminals of said transmitter

and including said condenser and the second winding of said induction coil, an impulse sender for producing interruptions in the said first bridge to transmit impulses over the line to the exchange, the said second bridge remaining closed meanwhile, and contacts actuated only during the operation of said sender for short-circuiting said receiver.

8. In a substation telephone set, an induction coil, a transmitter, a receiver, and one winding of said induction coil in bridge of the line, a ringer and a condenser in a second bridge of the line, a local circuit connecting the two terminals of said transmitter and including said condenser and the second winding of said induction coil, an impulse sender for producing interruptions in the said first bridge to transmit impulses over the line to the exchange, the said second bridge remaining closed meanwhile, and contacts actuated only during the operation of said sender for short-circuiting both the receiver and the transmitter.

9. In a substation telephone circuit, an induction coil, a transmitter, a receiver, a normally open bridge of the line including said transmitter, said receiver, and one winding of said coil, a pair of switch hook contacts for closing said bridge, a ringer and a condenser included in a permanently closed bridge of the line, a calling device in series with one line conductor, a second pair of switch hook contacts, and a normally open shunt for said transmitter including both said pairs of switch hook contacts, said calling device, said condenser, and the other winding of the said induction coil.

10. In a telephone substation set, a transmitter, a receiver, an induction coil, a line circuit across which are bridged said transmitter, receiver and one winding of said induction coil in series, a second bridge connected permanently across said line comprising a condenser and a ringer, and means comprising an impulsing device for transmitting impulses over said line circuit to the exchange, said condenser and the second winding of said induction coil forming a shunt path around said impulsing device.

11. In a substation circuit arrangement, two line conductors, a bridge across said conductors including the primary winding of an induction coil, a microphone and a telephone receiver, a normally closed bridge across said conductors including a signal and a condenser, a third bridge including a secondary winding of said induction coil, said third bridge being connected to said second bridge at a point between said signal and said condenser, the other end of said third bridge being connected to said first bridge at a point between said microphone and said primary winding of said induction coil, a hookswitch serving to close said first

and third bridges, an impulse sender having a pair of impulse springs and a plurality of shunt springs arranged to be closed when said impulse springs are operated to render said microphone and telephone receiver inoperative, and an impulse path extending across said line conductors including a portion of said first bridge and extending through said pair of impulse springs.

12. In a substation circuit arrangement, two line conductors, a bridge across said conductors including the primary winding of an induction coil, a microphone and a telephone receiver, a normally closed bridge across said conductors including a signal and a condenser, a third bridge including a secondary winding of said induction coil, said third bridge being connected to said second bridge at a point between said signal and said condenser, the other end of said third bridge being connected to said first bridge at a point between said microphone and said primary winding of said induction coil, a hookswitch serving to close said first and third bridges, an impulse sender having a pair of impulse springs and three normally open shunt springs arranged to be closed when said impulse springs are being actuated, said shunt springs when closed functioning to render said microphone and telephone receiver inoperative, and an impulse path across said line conductors including a portion of said first bridge and extending through said impulse springs and through the shunt springs.

13. In a substation circuit arrangement, an induction coil, a signal and a condenser forming one unit, a microphone, a telephone receiver, an impulse sender, and a switch-hook forming a second unit, two line conductors, a bridge across said conductors including the primary winding of said induction coil, said microphone and said telephone receiver, a normally closed bridge across said conductors including said signal and said condenser, a third bridge including the secondary winding of an induction coil connected across said first and second bridges, said hookswitch functioning to close said first and third bridges, an impulse sender having a pair of impulse springs and a plurality of shunt springs arranged to be closed when said impulse sender is operated, said shunt springs when closed serving to render said microphone and said telephone receiver inoperative, an impulse circuit including a portion of said first bridge and extending through said impulse springs, the connections for said bridges between said first and second units including not more than four conductors.

In witness whereof, I hereunto subscribe my name this 18th day of May, A. D., 1922.

ARTHUR BESSEY SMITH.
